UNITED STATES PATENT OFFICE

PAUL MOUTON, DECEASED, LATE OF PARIS, FRANCE, BY JACQUES MOUTON, ADMINISTRATOR, OF PARIS, FRANCE, ASSIGNOR TO CHENEY BROTHERS, OF NEW YORK, N. Y., A CORPORATION OF CONNECTICUT

DESIGN FOR A TEXTILE FABRIC

Application filed February 1, 1933. Serial No. 47,069. Term of patent 3½ years.

To all whom it may concern:

Be it known that, PAUL MOUTON, deceased, late a citizen of France and residing at Paris, 29 Rue du Sentier, has invented a new, original, and ornamental Design for Textile Fabrics, of which the following is a specification, reference being had to the accompanying drawing, forming part thereof.

The figure is a plan view of a textile fabric, showing the new design.

What is claimed is:

The ornamental design for a textile fabric, substantially as shown.

JACQUES MOUTON,
Administrator of the Estate of Paul Mouton, Deceased.
